UNITED STATES PATENT OFFICE.

OLIVER D. LOMBARD AND SYLVESTER POLLARD, OF LOWELL, MASS.

PICKER-STAFF CHECK FOR LOOMS.

SPECIFICATION forming part of Letters Patent No. 297,821, dated April 29, 1884.

Application filed August 20, 1883. (No model.)

To all whom it may concern:

Be it known that we, OLIVER D. LOMBARD, a citizen of the United States, and SYLVESTER POLLARD, a subject of Victoria, Queen 5 of the United Kingdom of Great Britain and Ireland, and both residing at Lowell, in the county of Middlesex and Commonwealth of Massachusetts, have invented a certain new and useful Improvement in Picker-Staff Checks for 10 Looms, of which the following is a specification.

Our invention consists of means of securing the picker-check to the lay-beam, and of means of varying the resistance of the check.

15 In the accompanying drawings, Figure 1 is a front elevation of a part of the frame and the lay of a loom, showing a picker-staff, shoe, shoe-strap, roll, and our invention attached to the lay-beam. Fig. 2 is a longitudinal section of one end of the lay-beam through the picker-staff slot, showing the cap and our invention attached to the lay-beam. Fig. 3 is a cross-section of the lay-beam and the cap through the picker-staff slot, showing our invention attached to the lay-beam, a part of the block and the horizontal portion of the 25 spring being broken away. Figs. 4 and 5 are views like Figs. 2 and 3, respectively, except that in Figs. 4 and 5 a different form of picker-staff check is shown.

30 In Fig. 1, A is a part of the loom-frame; B, the lay-shaft, provided with the extension B'; B², the sword of the lay; C, the picker-staff; C', its shoe. D is a strap, the end of 35 which is secured to the lower end of the picker-staff; D', a roller, on which the strap D is wound, as usual, by a spiral spring. (Not shown.) B⁴ is the slot in which the upper end of the picker-staff oscillates. B⁵ is the metallic cap which forms the bottom of the shuttlebox and incloses the end of the lay-beam.

40 All of the above-named parts are of the usual construction and operation.

The picker-staff check shown in Figs. 1, 2, 45 and 3 consists of a spindle, E, near the ends of which are attached the ends of a spring-wire, F, the wire passing through holes E' in said spindle, and being then wound around the spindle in two spirals, F² F³, toward each other, one spiral 50 being right-handed and the other left-handed, and the middle uncoiled part or arm, F', of

the wire being nearly of a U shape, and having a straight horizontal part, F⁴, against which the picker-staff strikes in its outward motion, this part F⁴ being covered with leather 55 F⁵, to deaden the noise of the picker-staff striking it and prevent wear of said staff and part. The spindle E is supported by being passed horizontally through the block G, provided with a tapering shank, G', having four ears, 60 g g' g', two on each side of said shank, in opposite pairs, the distance between the upper pair, g g, and the lower pair, g' g', being equal to the combined thickness of the lay-beam and its cap. The shank G' is passed endwise 65 up through the slot B⁴, with its flat faces lying lengthwise of the slot, and then turned at right angles, so that its upper ears will rest upon the top of the cap, and the lower ears will fit closely against the under side of the 70 lay-beam, the shank being retained in place by friction between it and the lay-beam.

To make the shank more secure in its place, a piece of rawhide or leather, H, (which also serves as a buffer for the picker-staff to strike 75 against,) is crowded into the slot against the shank.

It will be seen that the above-described device affords a means of attaching a picker-staff check to the lay-beam without the use 80 of screws or bolts such as are commonly used. The objection to the use of screws and bolts is that they are continually getting loose and breaking, requiring the loom to be stopped for repairs and causing great inconvenience 85 and expense. The spindle is prevented from turning in the block by a set-screw, I, which, entering a threaded hole in said block, thrusts against said spindle. By loosening the set-screw and turning the spindle very slightly, 90 the resistance which the check offers to the blow of the picker-staff may be varied, because turning the spindle varies the angle at which the check stands when it is struck by the picker-stick.

95 In Figs. 4 and 5 the check consists of two circular cams, N N', one, N, of which is cast or otherwise formed in one piece with the shank G, and the other, N', of which is provided with a radial arm, N², to receive the 100 blow of the picker-staff. A stud or spindle, O, is firmly secured in the stationary cam N,

and on this spindle the other cam, N', turns, being pressed up against the stationary cam by a spiral spring, P, surrounding said spindle, and compressed between the movable cam 5 and a pin, O', which is driven through said spindle. A washer, O'', may be placed between the pin O' and the spring P. Various other well-known forms of checks may be attached to the lay-beam in the same manner.

10 We claim as our invention—

1. A picker-staff check provided with a shank adapted to reach through the picker-staff slot of a lay-beam, and having means to engage directly with said lay-beam, substantially as specified.

15 2. A picker-staff check provided with a shank adapted to reach through the picker-staff slot of the lay-beam, and having a pair

of ears adapted to rest upon the top of said beam or its cap, and having another pair of 20 ears adapted to press against the under side of said lay-beam, substantially as specified.

3. The combination of the wire bent into connected spirals, and having an arm, the spindle provided with holes to receive the 25 ends of said wire, the block, means of attaching said block to a lay-beam, and a set-screw turning in said block and thrusting against said spindle, substantially as and for the purpose specified.

OLIVER D. LOMBARD.
SYLVESTER POLLARD.
